UNITED STATES PATENT OFFICE.

KARL OSWALD, OF IRVINGTON, NEW JERSEY.

FASTENER FOR HAND-BAGS AND THE LIKE.

1,137,419.

Specification of Letters Patent. Patented Apr. 27, 1915.

Application filed December 31, 1913. Serial No. 809,608.

To all whom it may concern:

Be it known that I, KARL OSWALD, a citizen of the United States, and a resident of Irvington, in the county of Essex and State of New Jersey, have invented certain Improvements in Fasteners for Hand-Bags and the like, of which the following is a specification.

The objects of this invention are to combine in such a fastener a primary and secondary lock; to enable them to coöperate in action, and to have both of them positioned by the same spring; to cause the primary lock to carry the secondary lock and bring it into position for locking, and to cause the secondary lock to afford finger means for operating the primary lock; to secure a compact structure which shall give a neat and pleasing appearance upon the bag; to 10 secure a simple construction which can be advantageously manufactured, and to obtain other advantages and results as may be brought out in the following description.

Referring to the accompanying drawings, in which like numerals of reference indicate the same parts throughout the several figures, Figure 1 is a perspective view of a bag frame with its members locked together by my improved fastener; Fig. 2 is a perspective view of the same with the members 20 opened; Fig. 3 is a cross-sectional view of the frame and its fastener taken on line A—A, Fig. 7; Figs. 4, 5, and 6 show successive steps in releasing the fastener to 25 open the bag; Fig. 7 is a longitudinal section on line B—B of Fig. 3; Fig. 8 is a detail view of a certain pivotal rivet for connecting the two arms of the secondary lock, and Fig. 9 is a similar detail perspective 30 view of a certain torsional spring.

In the specific embodiment of the invention illustrated in said drawings, the reference numerals 1, 2 indicate frame sections of a hand bag or the like, said sections being 35 hinged together at their ends, as at 3, 3, as usual. The present invention contemplates novel means for preventing inadvertent swinging apart or opening of these frame sections, either by accident or thieves, with- 40 out attracting the attention of the party carrying the bag, and for this purpose I provide a primary locking member 4, the opening of which is prevented by a secondary locking member 5, both carried by 45 one frame section, as 1, and adapted to engage the other section 2. Said primary

locking member preferably comprises a knob 6 resiliently carried upon the top of the frame section 1, and adapted to overlie the top of both frame sections when they 50 are closed together. For pivotally and resiliently mounting said knob 6, I secure to the top of the frame section 1 two posts 9, 10 spaced apart longitudinally of the bag frame, and provided with sockets 11, 12 in 55 their facing sides. Extending between these posts 9, 10 and rotatably held within the sockets 11, 12 is a hollow bar 13, retained against longitudinal movement by the posts themselves and extending eccentrically through the knob 6, that is, the bar passes through the knob below and to one side of the center thereof. Preferably the knob is secured, as by soldering, midway of the length of the bar 13, but obviously such 65 details may be varied without departing from the spirit and scope of the invention. Arranged longitudinally within the hollow bar 13 is a torsional spring 14, preferably comprising a piece of flattened wire, secured at one end to the bar 13 and at the other end to the bag frame section 1 in any suitable manner, such for instance as shown more particularly in Figs. 7 and 9. This 70 consists in clamping the end of the spring 14 within the end of the bar 13 by flattening or squeezing the end of the bar against the end of the spring, it being preferable to restrict the flattened portion of the bar to the part thereof within the post 10 so as not to 75 affect the surface of the bar bearing in the socket 12. The other end of the bar 13 is left open and the spring 14 projects out of the same and is bent toward the bag-frame 80 section as at 15. If necessary, the bent end 85 15 is provided with a foot 16 which projects laterally to rest upon the top of the bag frame section 1 and aid in preventing turning of that end of the spring. Obviously a torsional or twisting movement of the hollow bar 13 and knob 6 will be resisted by the spring 14, and said bar and knob will 90 normally assume a given position, which of course is upright with respect to the bag frame and such that the knob overlies both 95 of the frame sections when they are closed together.

In the under side of the knob 6 is a notch or recess 17, and projecting from the top of the bag frame section 2 is a stud or detent 110 28 adapted to snap into the recess 17 and coöperate with the primary locking member

described, to releasably hold the frame sections together, as will be understood by those skilled in the art. In order to lock this primary lock against inadvertent opening I provide the secondary lock 5 which comprises a pair of substantially parallel arms 18, 18 pivoted to the knob 6, on an axis transverse to the bag frame and adapted to be swung downward to lie on opposite sides of the frame sections, as shown in Figs. 1 and 3. Obviously the knob will be prevented from tilting, with the arms in locking position shown in Figs. 1 and 3, and in addition the bag frame sections are positively held together between the arms 18, 18. Said arms are preferably mounted upon a pivotal rivet 19 extending transversely through the knob 6 and provided with squared ends 20 on which the arms 18, 18 are non-rotatably secured as by heading over the ends of the rivet 19, and consequently both arms will swing in unison. It will of course be understood that said arms swing in the plane of the bag frame, and to retain the same in locking position, I preferably stamp protuberances 21, 21 upon opposite outer sides or flanges of the bag frame sections, and hollow out the inside faces of the arms as at 22, 22 to take over such protuberances. Enough effort has to be exerted to disengage the arms from these protuberances so that accidental opening of the bag is prevented and the likelihood of thieves gaining access to the interior 35 of the hand-bag unnoticed is remote.

In order to add to the neat and attractive appearance of the device, I preferably shape the knob substantially spherical except for its two opposite sides which are flattened 40 to provide bearing surfaces for the arms 18, 18, and the pivotal rivet for these arms preferably extends diametrically through the center of the sphere. The arms are then shaped at their pivoted ends to conform 45 with the contour of the knob, and in this manner, when the arms are swung up into open position, the surface of the arm forms a continuation of the curved under surface of the knob and allows the stud or detent to 50 wedgingly engage the arm and pass into engagement with the knob as the bag is being closed.

In operation, the bag being closed, as shown in Figs. 1 and 3, the arms 18, 18 are first swung upward as shown in Fig. 4, although said arms need not be swung through 180° as shown, but can be swung only about 90°; furthermore, said arms can be swung in either direction, and it is not necessary 55 to take hold of both of them, since if one is swung the other moves with it. After the arms have been disengaged from the frame section 2, the primary locking member is disengaged, by simply tilting it in a manner 60 already well-known in the art and illus-

trated in Fig. 5, and in said tilting the arms 18, 18, in whatever position they may be, afford a finger hold for exerting the necessary pressure. The bag handle (not shown) is of course attached to the frame section 2, 70 as by means of the ears 23, 23, so that it may be drawn upon, if desired, with one hand at the same time the other hand is manipulating the fastener, and the bag thus opened as shown in Fig. 6. It has 75 been found in practice that my improved construction, made as described, and with the tops of the posts 9, 10 closed and rounded, not only presents a very neat and pleasing appearance but is also agreeable 80 to the touch in operating.

Various modifications of details can of course be made by those skilled in the art without departing from the spirit and scope of the invention, and I do not wish to be 85 understood as limiting myself except as required by the following claims when construed in the light of the prior art.

Having thus described the invention, what I claim is:

1. The combination with a pair of hinged frame sections, of a primary locking member on one of said sections arranged and adapted to tilt in a plane transverse to said sections and normally engaging the other 90 section to prevent separation of the said sections, and a secondary locking member mounted on said primary locking member to swing in the plane of the frame sections and lie outside the same when they are 100 closed.

2. The combination with a pair of hinged frame sections, of a primary locking member on one of said sections arranged and adapted to tilt in a plane transverse to said sections and normally engaging the other section to prevent separation of the said sections, and an arm mounted on said primary locking member to swing in the plane of the frame sections and lie outside the section which 105 does not carry the primary locking member when said sections are closed.

3. The combination with a pair of hinged frame sections, of a primary locking member on one of said sections arranged and adapted to tilt in a plane transverse to said sections and normally engaging the other section to prevent separation of the said sections, and a secondary locking member comprising 110 opposite arms mounted on said primary locking member to swing in planes parallel to the frame sections and lie outside the same when they are closed.

4. The combination with a pair of hinged frame sections, of a primary locking member on one of said sections arranged and adapted to tilt in a plane transverse to said sections and normally engaging the other section to prevent separation of the said sections, and a secondary locking member comprising 115 120 125 130

arms at opposite sides of said primary locking member adapted to swing in planes parallel to the frame sections and lie outside the same when they are closed, and pivoting 5 means extending between said arms through said primary locking member and holding the arms against turning independently of each other.

5. The combination with a pair of hinged 10 frame sections, of spaced posts on one of said sections, a hollow bar having its ends journaled in said posts, a torsion spring in-

side said hollow bar, said spring engaging the hollow bar at one end to turn therewith and at its other end engaging a fixed part to 15 prevent turning, and a body on said hollow bar adapted to engage the other frame section and releasably hold said sections against separation.

KARL OSWALD.
